CLASPER MECHANICAL SHOELACE

Peter Konovaloff, Flushing, N. Y.

Application March 31, 1939, Serial No. 265,123

8 Claims. (Cl. 24—207)

This invention relates to new and useful improvements in a clasper mechanical shoe lace or the like.

More specifically, the invention proposes the construction of a clasper mechanical shoe lace or the like characterized by a means for quickly and conveniently closing the opening of a shoe without the necessity of passing laces through eyelets and tying the same.

Still further it is proposed to provide a pair of frame arms mounted on the sides of the opening and hingedly connected together at their ends and provided with a lazy tong structure mounted in track grooves extending along the adjacent edges of said frame arms in a manner to draw said frame arms together when said lazy tong structure is pulled manually outwards.

Still further it is proposed to provide catches mounted on the outer ends of the frame arms for holding the outer ends of the lazy tong structure and having operator heads for releasing the same and upon which a member is adapted to be engaged in a manner to prevent said catches from being accidentally disengaged.

Still further it is proposed to provide a flexible strand having its ends attached to the outer ends of said lazy tong structure in a manner to be used for pulling said lazy tong structure for urging said frame arms together.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a shoe having a clasper mechanical shoe lace constructed according to this invention.

Fig. 2 is an enlarged elevational view of the clasper mechanical shoe lace in its closed position.

Fig. 3 is a view similar to Fig. 2 but illustrating an open position of the parts.

Fig. 4 is a view looking in the direction of the line 4—4 of Fig. 2.

Fig. 5 is a sectional view on the line 5—5 of Fig. 2.

Fig. 6 is a sectional view of one of the pivotal connections for the lazy tong structure.

Fig. 7 is a sectional view on the line 7—7 of Fig. 2.

Fig. 8 is a sectional view on the line 8—8 of Fig. 7.

Fig. 9 is a sectional view on the line 9—9 of Fig. 3.

Fig. 10 is a view similar to Fig. 7 illustrating a modification of the invention.

Fig. 11 is a view similar to a portion of Fig. 2 but illustrating a further modification of the invention.

Fig. 12 is a sectional view on the line 12—12 of Fig. 11.

The clasper mechanical shoe lace or the like comprises a pair of frame arms 10 for attachment along the sides of an opening formed in a shoe 11 or other similar article. The frame arms 10 have their sides mounted upon the sides of the opening and are hingedly connected together at their inner ends. A link 12 extends between the adjacent edges of the inner ends of the frame arms 10 and is pivotally supported upon a pin 13 extending through each of the frame arms 10.

A lazy tong structure is mounted at its inner end upon an inner portion of the frame arms and has follower elements on its sides extending along track grooves formed along the adjacent faces of the frame arms 10. The lazy tong structure is 25 constructed of a plurality of lengths of metal 14 arranged in a zig-zag relationship to each other. The innermost metal members 14 are pivotally connected to pins 15 which extend through the frame arms 10. The adjacent ends of the metal 30 members 14 are pivotally connected together by means of followers 16. Each follower 16 comprises a pin 16^a which extends through enlarged openings formed in the ends of the metal members 14. Head elements 16^b are mounted upon 35 the ends of the pin 16^a and pivotally maintain the metal members thereon. Each of the frame arms 10 has its edges 10^a bent inwards forming track grooves 17 in which the followers 16 ride for drawing the frame arms 10 together when the 40 lazy tong structure is pulled outwards. It will be noted that each successive metal member 14 forming the lazy tong structure is slightly larger than the one immediately adjacent, which permits the lazy tong structure to assume a V-shape 45 when the frame arms are in their open position. This is clearly shown in Fig. 3.

Catches are mounted on the outer ends of the frame arms for holding the outer ends of the lazy tong structure. Each of these catches comprises 50 a flexible plate 18 mounted adjacent the outer ends of the frame arms 10 and which is provided with a plurality of teeth 18^a which are adapted to engage the outermost follower 16 of the lazy tong structure for holding the frame arms in 55

their closed position. A leaf spring 19 is mounted within a cavity 20 formed within the frame arms 10 for urging the plates 18 into their operative positions. Each of the plates 18 is provided with an operator head 21 in the form of a handle which extends beyond the end of the frame 10 and which are adapted to be urged apart for spreading the plates 18 to release the holding action of the spring and free the lazy tong structure to permit the frame arms 10 to be opened.

10 A flexible strand 22 in the form of a string has its ends attached to the outermost followers 16 of the lazy tong structure and is adapted to be used for pulling the lazy tong structure to close the frame arms 10. A member 23 having openings 24 through which the strand 22 slidably passes is adapted to be slid upon the strand and engaged against the ends of the frame arms for holding the same in their closed position as shown in Fig. 2. This member 23 also has a second pair of openings 25 which are adapted to be engaged upon the operator heads as shown in Fig. 7 for preventing the same from spreading apart to release the holding action of the teeth 18.

20 The member 23 is provided with a means for locking the same in fixed positions upon the strands 22 for preventing the same from sliding thereon. This means comprises a plug 26 rotatively extended through the member 23 and at right angles to the openings 24. This plug 26 extends partially through the openings 24 and is provided with cutout portions 26a which are adapted to be aligned with the openings 24 for permitting the strand to freely slide therein. However, if the plug 26 is turned to disalign the cutouts 26a from the openings 24 the member 23 will be clamped in position upon the strand 22. This clamping action also prevents the member 23 from disengaging the operator heads 21. A ring 27 is mounted upon the plug 26 and permits the same to be conveniently turned for aligning and disaligning the cutouts 26a with the openings 24.

45 The operation of this form of the invention is as follows:

The lazy tong structure is moved to permit the frame arms to be opened so that one's foot may be slipped into the shoe 11. The frame arms 10 are then closed by pulling the strand 22 manually outwards so that the lazy tong structure 14 will urge the frame arms 10 together. Then the member 23 is slid inwards upon the strand 22 to engage the openings 25 upon the operator heads 21 of the plates 18 to hold them in their operative position. The plates 18 have teeth 18a which engage the outermost follower 16a of the lazy tong structure serving to prevent the same from moving inwards. The plug 26 is then rotated to disalign the cutouts 26a from the openings 24 to align the member 23 in position upon the strand 22 and assist in holding the lazy tong structure.

According to the modification of the invention shown in Fig. 10 the construction of the clasper mechanical shoe lace is similar to that previously described and distinguishes therefrom merely in the construction of the plug 26' used for clamping the member 23 in position on the strand 22. In this form of the invention the plug 26' is 70 threadedly engaged into the top face of the member 23 and is adapted to be tightened against the strand 22 for holding the member 23 in position thereon. In other respects this form of the invention is similar to the previous form.

75 According to the modification of the invention

shown in Figs. 11 and 12 the plates 18' are mounted upon the bottom wall of the vertical arms 10 and each of the arms 10 is provided with a recessed portion 10b for permitting the plate to be moved downwards to free the lazy tong structure. The outermost follower 16 of the lazy tong structure is provided with a catch element 28 having a portion cooperative with the teeth 18a of the plate 18'. The ends of the strand 22 are also connected with the catch element 28 of the lazy tong structure. The member 23 which is used for holding the operator heads 21 is provided with an inwardly extending projection 23a engageable into the ends of the frame arms 10 to prevent movement thereof and hold the plates 18' against flexing to release the catch elements 28 until such time as the member 23 is removed from the ends thereof. In other respects this form of the invention is similar to the previous forms.

20 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

30 1. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads.

40 2. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

50 3. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

60 4. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

70 5. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

80 6. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

90 7. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

100 8. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said lazy tong structure comprising a plurality of metal members extended between the adjacent sides of said frame arms and having their adjacent ends pivotally mounted upon said follower elements.

- portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed position on said strands, and said member having openings engageable with said operator heads for locking said operator heads, said lazy tong structure comprising a plurality of metal members extended between the adjacent sides of said frame arms and having their adjacent ends pivotally mounted upon said follower elements, said follower elements comprising a pin extending through the adjacent ends of said metal members, and head elements mounted upon the ends of said pins and engaging the said track grooves.
4. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said track arms having portions thereof bent inwards forming said track grooves.
5. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said catches comprising plates mounted within said frame arms and being provided with teeth engaging the outermost follower element of said lazy tong structure, and a resilient means for urging said plates into an operative position.
6. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said means for locking said member comprising a plug extending through said member and cutouts formed in said plug and alignable with said openings through which said strands pass, and means for rotating said plug to disalign said cutouts from said openings to clamp said strands.
7. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said means for locking said member comprising a plug threadedly engaged into said member and engageable upon said strands for holding the same.
8. A clasper mechanical shoe lace or the like, comprising a pair of frame arms for attachment along the sides of an opening and hingedly connected together at their ends, a lazy tong structure mounted at its inner end upon an inner portion of said frame arms and having follower elements on its sides engaging track grooves extending along the adjacent faces of said frame arms, catches mounted on the outer ends of said frame arms for holding the outer end of said lazy tong structure and having operator heads for releasing the catches, flexible strands attached to the outer ends of said lazy tong structure, a member slidably mounted on said strands, means for locking said member in fixed positions on said strands, and said member having openings engageable with said operator heads for locking said operator heads, said catches comprising catch elements mounted upon the outermost follower elements of said lazy tong structure, a plate mounted on the base wall of said frame arms, and teeth on each of said plates and engageable by said catch elements.

PETER KONOVALOFF.
